UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

TURBINE.

1,209,402. Specification of Letters Patent. Patented Dec. 19, 1916.

Application filed December 7, 1914. Serial No. 875,758.

To all whom it may concern:

Be it known that I, CHARLES W. DAKE, a citizen of the United States, residing at Chicago, in the county of Cook and State 5 of Illinois, have invented a certain new and useful Improvement in Turbines, of which the following is a specification.

My invention relates to improvements in turbine wheels and process of producing the 10 same and has for one object to provide a new and improved type of turbine wheel which will be light, durable and inexpensive to manufacture. Other objects of my invention will appear in the specification.

15 The invention is illustrated more or less diagrammatically in the accompanying drawings, wherein—

Figure 1 is a side elevation of a portion of a turbine wheel; Fig. 2 a section on the 20 line 2—2 of Fig. 1; Fig. 3 is a plan view of a turbine bucket; Fig. 4 is a section on the line 4—4 thereof; Fig. 5 is a section on the line 5—5 of Fig. 4; and Fig. 6 is a rear elevation of one of the buckets.

25 Like parts are indicated by like figures throughout the several figures.

A is a wheel reinforced at A¹ mounted on a hub A² annularly channelled at its outer periphery A³.

30 B is a bucket carrying ring substantially concentric with and contained within the channel A³.

B¹ are screws holding the ring removable in the channel.

35 B² are buckets strung or mounted on the annular ring having rearwardly extending ears B³ embracing the ring on either side.

B⁴ is a section removable from the ring held separately in the channel in line with 40 the remainder of the ring to provide an aperture through which the buckets may be inserted on or withdrawn from the ring. The buckets are normally free to slide about the ring but held thereon by rearwardly extending embracing ears. The mounting or 45 bucket ring conforms generally to the contour of the bucket ears and when drawn tight upon the wheel is wedged within the channel or groove and clamps the buckets 50 firmly in position.

It will be evident that while I have shown in my drawings an operative device, still many changes might be made both in size, shape and arrangement of parts without departing from the spirit of my invention and

I wish, therefore, that my drawings be regarded as in a sense diagrammatic.

The use and operation of my invention are as follows: Starting with the mounting ring the turbine buckets are one at a time 60 slipped upon it and along it so that the rearwardly extending ears thereon embrace the ring. This continues until the entire ring is covered by a series of buckets arranged side by side. The removable section of the 65 ring is also covered and then the ring thus formed and assembled and carrying the buckets separably secured thereon is separably secured to the rotor or wheel on a face thereof and lying in its plane of rotation by the screws as shown. These screws being then tightened up clamp the ring to the wheel and clamp the buckets between the ring and the wheel to hold them in fixed operative relation. 75

I claim:

1. A turbine including a turbine wheel, buckets for the turbine wheel, and a mounting ring separably secured to the turbine wheel and to which mounting ring the buckets are separably secured, said buckets having rearwardly extending ears embracing the ring. 80

2. A turbine including a rotor, turbine buckets, and a mounting ring separably secured to the rotor at a face thereof that lies in the plane of rotation of the rotor and upon which mounting ring the buckets are separably secured to one side of the rotor, the mounting ring and buckets having interconnection permitting the buckets to be moved along the mounting ring, while supportingly engaged therewith, for the purpose of mounting and demounting the buckets. 85 90 95

3. A turbine including a rotor, turbine buckets and a mounting ring carried by the rotor at a face thereof that lies in the plane of rotation of the rotor and upon the outer side of which mounting ring the buckets 100 are separably secured to one side of the rotor and ring, the mounting ring and buckets having interconnection permitting the buckets to be moved along the mounting ring, while supportingly engaged therewith, for 105 the purpose of mounting and demounting the buckets.

4. A turbine including a rotor, turbine buckets, and a mounting ring carried by the rotor at a face thereof that lies in the 110

plane of rotation of the rotor and upon the outer side of which mounting ring the buckets are separably secured to one side of the rotor and ring, said buckets having rearwardly extending ears embracing the ring.

5. A turbine including a rotor, turbine buckets, and a mounting ring separably secured to the rotor at a face thereof that lies in the plane of rotation of the rotor and 10 upon the outer side of which mounting ring the buckets are separably secured to one side of the rotor and ring, said buckets having rearwardly extending ears embracing the ring.

15. 6. A bucket wheel for turbines and the like comprising a wheel body channeled at its outer periphery, a removable ring and means for removably holding it in said channel, a series of turbine buckets removably 20 mounted upon said ring, said buckets being held upon said ring by rearwardly extending ears which embrace it.

7. A bucket wheel for turbines and the

like comprising a ring, means for attaching it to the wheel and a series of buckets 25 separably secured to the ring, said buckets having rearwardly extending ears which embrace the ring.

8. A bucket wheel for turbines and the like comprising a rotor body channeled near its periphery, a ring and means for removably mounting it in said channel and a series of turbine buckets mounted upon said ring so as to be movable therealong, said parts being constructed and arranged to be 30 complete with but a single ring, said buckets being operatively secured in place by 35 said single ring.

In testimony whereof I affix my signature in the presence of two witnesses this 4th day 40 of December, 1914.

CHARLES W. DAKE.
